UNITED STATES PATENT OFFICE.

MICHAEL MEYER, OF WAUKESHA, WISCONSIN.

DRAWER.

SPECIFICATION forming part of Letters Patent No. 310,299, dated January 6, 1885

Application filed April 16, 1884. (No model.)

To all whom it may concern:

Be it known that I, MICHAEL MEYER, of Waukesha, in the county of Waukesha and State of Wisconsin, have invented certain new and useful Improvements in Drawers, of which the following is a full, clear, and exact description.

The object of my invention is to provide simple, inexpensive, and self-acting devices for attachment to drawers and their frames or slideways, whereby the drawers will be compelled to move alike at both ends as they are drawn out from and slid back into closed position.

15 The invention consists in a pair of intermeshing toothed sectors pivoted to fixed cleats or cross-bars of the drawer-frame and to the drawer by links, whereby a parallelism of movement of the drawer is secured, all as hereinafter fully described and claimed.

Reference is to be had to the accompanying drawings, forming part of this specification, in which similar letters of reference indicate corresponding parts in both the figures.

25 Figure 1 is a front elevation of a chest of drawers, partly broken away, and showing my improvement applied; and Fig. 2 is a sectional plan view on the line *x x*, Fig. 1.

The letter A indicates the drawers of an ordinary bureau or cabinet, which are fitted in place to slide in the frame B, said frame B having the front spacing-pieces, *b*, between the drawers, and also having the side cleats, *c*, forming the rests or ways on which the drawers slide. The drawers A are of the usual pattern, their bottoms *a* being grooved into the sides *a'*, leaving a space between the drawer-bottom and the lower or working edges of the sides *a'* of about one-half inch, more or less.

30 In applying my improvement I fasten to the drawer-frame B the cross-cleats C, which are of about the same thickness as the spacing-pieces *b* between the drawers, and to these cleats C, I pivot on pins *c'* the sector-plates D, which have intermeshing teeth *d*, and are connected by pins *e* to bars or links E, which latter are in turn pivoted to the drawer-bottom *a*, at *f*, near the front of the drawer, as clearly shown in the drawings. With this construction, as the drawer A is pulled out or pushed

45 in the links E will turn the sectors D and cause both ends of the drawer to move alike,

or, in other words, to maintain a parallelism with the front face of the drawer-frame, and the action will be alike in this respect whether 55 the drawer A be worked by grasping the knobs or pulls *g g* at both ends of the drawer or at either end only, as will readily be understood. The sectors D and links E require no more room for their application than is usually left 60 vacant below the bottom of the drawer, and as the supporting cleats or plate C need be no thicker than the spacing-pieces *b* between the drawers, my improvement may be applied to drawers of any size without requiring a special 65 enlargement of the parts, and the improvement may also as readily be applied to the drawers of old articles of furniture already in use as to new goods.

As shown, the intermeshing sector-plates D 70 consist of thin flat pieces of wood; but they may be cast of any suitable metal and in open pattern work, making them very light in weight, and still sufficiently strong for the work required of them.

75 My invention may be applied to single drawers adapted for use in any situation, as well as to chests or tiers of drawers, as represented in the drawings, and drawers having my improvement applied need not be fitted so snugly 80 in their frame, and still work equally well or much easier than drawers most carefully fitted in the usual way.

Having thus fully described my invention, I claim as new, and desire to secure by Letters 85 Patent—

1. The combination, with a drawer and drawer-frame, of intermeshing toothed sectors D, pivoted to the drawer-frame, and having their outer ends connected to the bottom of 90 the drawer, whereby a parallelism with the front face of the drawer is maintained, as set forth.

2. The combination, with the drawer A and the drawer-frame B, provided with the cleats C, of intermeshing toothed sectors D, pivoted to said cleats, and the links E, pivoted to the outer ends of the sectors and to the drawer-bottom, substantially as described.

MICHAEL MEYER.
